MOVABLE MEANS FOR SUPPORTING
DRAPERIES

Orville T. Stall, St. Paul, Minn.

Application July 5, 1946, Serial No. 683,807

4 Claims. (Cl. 160—125)

1

My invention relates to movable means for supporting draperies and has for its object to provide means for mounting the draperies in set extended position, in combination with means for moving the draperies so positioned and set laterally to expose all or any part of the window while not disturbing in any way the set of the draperies; and further to mount the draperies so set in pairs and to provide means for simultaneously moving the individual draperies of the pair either toward or away from each other.

In the present practice of mounting draperies it is customary to mount the draperies upon some supporting member such as a bracket-supported rod so as to either leave the entire window exposed or to cover part of the window on each side and to adjust the draperies for more or less window exposure by sliding or bunching together the individual draperies upon their support, thus substantially changing the set of the draperies.

A grave difficulty has been encountered in so mounting draperies in that the draperies can not be permanently set in position to afford the best and most attractive arrangement of folds and hanging loops but that the set of the draperies is changed every time they are adjusted on their supports. Sliding the draperies upon its support so as to in effect refold it together or unfold it can not be made without interfering with the best form of both folds and loops and getting the folds and loops out of balance and out of proportion.

I have discovered a very simple way of overcoming all of these difficulties and providing for the hanging of draperies in a fixed position with the folds and loops properly set for the most attractive and decorative drapery arrangement in combination with means whereby the entire drapery arrangement may be adjusted in unchanged condition laterally of the window to expose all of the window or only such parts of the window as it is wished to have exposed.

I accomplish this by the use of a U-bar having one of its arms slidable in a bracket fixed to the window frame and the other arm extending substantially parallel to the bracketed arm and carrying the draperies in a fixed arrangement of folds and loops, such that the drapery may be slid on the supporting arm to be entirely at one side of the window, leaving the window fully exposed, or it may be brought over a part of the window so, with two of such draperies positioned in the same manner, only such central part of the window as may be desirable to have exposed may be seen past the adjacent edges of the adjusted

2

drapery, all without in any way displacing or interfering with the drapery folds and loops as initially set.

I have further discovered that with this arrangement of hanging the draperies a system of cords and pulleys can be so secured to the drapery frame that pulling on the cord in one direction will simultaneously move the drapery frames away from each other to carry the draperies to the sides of the window and pulling on another cord will simultaneously move the draperies toward each other to cover a greater or less area of the window exposed between the edges of the draperies.

15 It is a principal object of my invention, therefore, to provide a U-member having one arm thereof held slidably within a bracket and having the other arm entirely free and adapted to receive on it one of a pair of draperies having a pre-formed permanent set to the folds and loops of the draperies.

15 It is a further object of my invention to mount on the drapery support arm a slide by which the length of that arm may be adjusted to accord with the desired width of the drapery member when the same is set.

25 It is a further object of my invention to provide a bracket having a pair of guide members spaced to receive for endwise movements an arm of a U-piece, upon the other arm of which the draperies will be folded and set, and to have in conjunction with said bracket a plate which may overlie the top of the window frame, to which the bracket member will be secured by any suitable means such as screws.

30 It is a further object of my invention to secure to the bracketed arm of the U-member a connector piece which is in turn connected with a cord in such manner that by traction on the cord the U-piece may be slid in the bracket member which supports it, to position the otherwise fixed draperies on the other arm of the U-piece, for the purpose of exposing more or less of the surface of the window adjacent which the draperies are hung.

45 It is a further object of my invention to employ a pair of said draperies and have a continuous cord member connected with each of the drapery-supporting U-pieces in such manner that by pulling the cord in one direction the U-piece and supporting draperies will be caused to move away from each other and by pulling on the cord in the opposite direction they may be caused to move toward one another.

50 It is a further object of my invention to provide

means for adjusting and holding in adjusted position the length of the cord connected with the U-pieces for accommodating the drapery-holding means to windows of different widths.

It is a further object of my invention to provide means connected with the draperies and having a loop formed thereon for conveniently attaching the draperies to the drapery-holding part of the U-pieces.

The full objects and advantages of my invention will appear in connection with the detailed description thereof which will now be given in the following specification; and the novel features by which the aforementioned advantageous and useful results are obtained will be particularly pointed out in the claims.

In the drawings illustrating an application of my invention in one of its forms:

Fig. 1 is a side elevation view of the drapery hanging means as positioned above a window with the draperies not attached.

Fig. 2 is a top plan view of what is shown in Fig. 1.

Fig. 3 is a sectional view taken on line 3—3 of Fig. 2 considerably enlarged.

Fig. 4 is a sectional view taken on line 4—4 of Fig. 1 very much enlarged.

Fig. 5 is an enlarged sectional view taken on line 5—5 of Fig. 1.

Fig. 6 is an enlarged sectional view taken on line 6—6 of Fig. 1.

Fig. 7 is a front elevation view of the arrangement with the draperies in position and the window substantially fully exposed.

Fig. 8 is an elevation view similar to Fig. 7 with the draperies drawn together.

Fig. 9 is a sectional view on an enlarged scale taken on line 9—9 of Fig. 8.

As illustrated, particularly in Figs. 1, 2 and 6, a bracket 10 is provided which has a top plate 11 adapted to extend over the top edge 12 of a window casing 13 and to be secured in position by screws 14. If desired, a filler piece 15, Fig. 6, may be placed upon the face of the casing member 13.

The face wall 16 of bracket 10 is formed with two pairs of lips 17 and 18, and 19 and 20 respectively which are spaced apart as indicated in Fig. 1. These lips are pressed out of the metal of the front wall 16 of the bracket 10, as shown at 21 in Fig. 6.

An arm 22 is formed on a U-piece 23 which is adapted to be mounted for longitudinal sliding movements inside of the respective sets of lips 17—18 and 19—20.

The U-piece 23 in addition to the arm 22 includes a broad semi-circular curved end 24, which curve can be made greater or less as desired to accommodate different types of draperies. The curve 24 is connected with a forwardly extending arm 25 which is parallel with arm 22 and has no connection with it excepting through the curve 24.

Upon the arm 25, as best shown in Figs. 1 and 2, is a sleeve 26 which slides with a close fit along arm 25 and is adapted to adjust the length of the arm to fit the width of draperies which will be employed. The sleeve 26 will preferably be finished at its inner end with an ornamental head 21.

The above arrangement may be complete in itself. There will be a U-piece unit mounted as above described at each side of the window, indicated generally at 28 and on these two members draperies indicated at 29 and 30 will be applied and permanently pleated as there shown.

The draperies will extend to and preferably around or partly around curved end 24 of the U-piece, to conceal operating parts, and will go out to the end of the extensible slide member 26.

When the U-piece is fully extended, as shown in Fig. 2, a stop member 31 will engage the end of the bracket 10 and prevent the U-piece from being pulled away from the window further. In that position the draperies at either side will hang flush with the side edges of the window leaving substantially the entire window exposed between the draperies.

This amount of exposure may be varied at will by simply sliding the U-pieces or the arms 22, thereof inwardly in the guide lips 17, 18 and 19, 20 formed on the bracket 10 until, if it is desired to cover the entire window with the draperies, they may be brought into the position indicated at 32 and 33 of Fig. 8 with a meeting line at 34.

The draperies are attached to the arm 25 or the composite arm 25, 26 in the manner shown in Fig. 9. A clip device 35 is provided with an outer loop 36 of spring metal and a lower clip lip 37, which, by spring action, will encircle and clamp to the U-piece arm 25 or the composite U-piece arm 25 and 26.

Secured to the loop 36 at its bottom by a continuing loop 38 is a pin 39 which may be passed through a stitching 40 on the draperies on the draping line 41. This holds the draperies, as at 29 and 30 of Fig. 7 and 32 and 33 of Fig. 8, in fixed folded and draped position on the bar 25 and the composite bar 25, 26.

The clip 37 will be expanded against spring tension in being pressed in position on the arm 25 or the composite arm 25, 26, and that spring tension applied to the flat arm 25 or the slide thereon 26 will hold the pinch pleats in fixed position and the drape as a whole permanently arranged regardless of the movements made of the U-piece support.

With this arrangement, as above pointed out, the position of the drape relative to the window opening can be easily adjusted to give more or less window opening without the need of moving or adjusting the arrangement of the drape upon the supporting arm 25 or combination arm 25, 26.

It is also true that a movement of the drapes toward each other and away from each other can be effected without in any way disturbing the window curtain or curtain rods or venetian blinds, if such are used.

While I have shown the bracket 10 as supported upon the top of the window casing, it is obvious that it may be supported by screws or other fastening means on the side of the window casing, and the guides on the bracket in relation to the support of the bracket on the window frame insure that the lines of the drapes top and bottom will run along lines of a true horizontal position.

It is, of course, practical, by removing the connector member or stop 31, to reverse the U-piece, putting the shorter arm 25 through the guide lips 17, 18 and 19, 20 and having the longer arm 22 receive the extension 26. This may be done where it is desirable for some reason to mount excessively wide drapes.

Normally window drapery consists of a pair of drapes one at each side of the window, and there will then be employed a pair of brackets 10 with their guide lips 17—18 and 19—20 as heretofore described. There also will be employed a second

U-member having a slide arm 42 and a connector

piece 43 corresponding to the connector piece 31 on slide arm 22 of U-piece 23.

It is desirable in the use of my invention to have means for easily and simultaneously moving the drapery-supporting members and the draperies thereon either toward each other to close off more or less of the exposed window surface, or away from each other to expose the window more or less. To accomplish this I use a system of cords shown in Figs. 1 and 2 and in some of their details in Figs. 3, 4 and 5.

This system embodies a cord strand 44 which is fastened to connector piece 43, as indicated at 45 in Fig. 2. The cord member 44 passes around a roller 46. The strand 44 beyond roller 46 continues as a second or return strand 47, Fig. 2, which is secured to the connector piece 31, as indicated at 48 in Fig. 2.

The connector piece 43, identical with connector piece 31, is shown in enlarged detail in Fig. 4, and as there shown, is secured to the slide arm 42 of the U-piece by means of a screw bolt 49. These connector pieces have at their top a right-angled plate 50 in which there is an opening 51 through which the cord 44 passes in a loop 53, as indicated in Figs. 1 and 4. This loop goes through an otherwise free ring 52, which, with opening 51, is the securing element.

This arrangement not only secures the cord strands 44 and 47 to the respective connector members 43 and 31, but secures them in a manner for ready adjustment for different width of windows and draperies.

As clearly indicated in Fig. 2, the cord strands 44 and 47 are spaced apart horizontally; and, as shown in Fig. 3, strand 44 goes over a grooved roller 54 and strand 47 goes over a grooved roller 55. The rollers 54 and 55 are mounted on a spindle 56 held by a plate 57 which is secured by screws on the top plate 11 of bracket 10.

The plate 57 projects beyond the end of bracket 10 so the rollers 54 and 55 are positioned to carry the end 58 of cord 44 outside but along the window casing 59, and in like manner the end 60 of cord 47 is carried parallel with end 58 of cord 44 alongside window casing 59. The end 58 has thereon a weighted handle 61 and the end 60 has thereon a weighted handle 62.

This arrangement is, as clearly indicated in Fig. 2, such that when handle 61 is pulled, cord 44 will draw the slide arm 42 in the direction toward the point of pulling while cord 47 having passed around roller 46 will, through connector 31, draw slide arm 22 in the opposite direction or away from the point of pulling, thus drawing the sets of draperies, held unchanged as to pleats and folds, toward each other to close off more or less of the window back of the draperies.

When the handle 62 is pulled the reverse operation takes place and the slides 42 and 22 are moved in opposite directions away from each other, and more or less of the window is uncovered.

The advantages of my invention have been made to appear quite clearly in the foregoing specification. The primary and fundamental advantage is that draperies may be set with their pinch pleats, folds and loops in the most advantageous and artistic manner and that adjustment of the drapes to cover more or less of the window may be effected without in any way disturbing the draperies as so set. A second great advantage of my invention resides in the fact that it enables the draperies to be positioned so as to entirely

cover or entirely open up the whole window with any desired intermediate positions.

A further very great advantage of my invention comes from the fact that pairs of draperies at each side of the window may be simultaneously moved to the same extent inwardly or outwardly toward and from the exact center of the window and always will be symmetrically positioned with reference to the window. These drapery holders are admirably suited to hang draperies at the sides of multiple windows, in which case, assuming there are three windows the draperies may be positioned to cover parts or all of the side windows.

15 I claim:

1. In combination with the top rail of a window casing, a drapery holder having a bracket portion overlying and secured to the top of said top rail, said bracket portion having a depending part extending vertically in spaced relation to the front of the casing, an open-ended guide secured to the side of said depending member, a slide member in said guide extended outwardly and having a supporting arm spaced from and held in parallel relation to the slide member with the space between them free and open at their inner ends for directly supporting a drapery, an actuator arm rigidly connected to the inner end of the slide member and extending to a point above the top of the top rail, a pair of pulleys on the top of the rail, a pair of cords each passing over and about a respective one of said pulleys, handles on said cords, whereby pulling down on one cord will move the entire structure including the drapery thereon in one direction and pulling down on the other cord will move it in the other direction.

2. In combination with the top rail of a window casing, a drapery holder having a bracket portion overlying and secured to the top of said top rail, said bracket portion having a depending part extending vertically in spaced relation to the front of the casing, an open-ended guide secured to the side of said depending member, a slide member in said guide extended outwardly and having a supporting arm spaced from and held in parallel relation to the slide member with the space between them free and open at their inner ends for directly supporting a drapery, an actuator arm rigidly connected to the inner end of the slide member and extending to a point above the top of the top rail, a pair of pulleys spaced laterally and having their axes above and parallel with the top of the top rail, a pair of cords each running over one only of said pulleys and extending vertically at the side of the window casing, said cords being in a position to be grasped by one standing beside the window, said cords being respectively connected with the slide and guided so that pulling down on one cord will move the slide, including the drapery thereon in one direction and pulling down on the other cord will move the slide in the other direction.

3. In combination with the top rail of a window casing, a drapery holder having a bracket portion overlying and secured to the top of said top rail, said bracket portion having a depending part extending vertically in spaced relation to the front of the casing, an open-ended guide secured to the side of said depending member, a slide member in said guide extended outwardly and having a supporting arm spaced from and held in parallel relation to the slide member with the space between them free and open at their inner ends for directly supporting a drapery, an actuator arm rigidly connected to the inner end

of the slide member and extending to a point above the top of the top rail, a pair of pulleys spaced laterally and having their axes above and parallel with the top of the top rail, a pair of cords each running over one only of said pulleys and extending vertically at the side of the window casing, said cords being in a position to be grasped by one standing beside the window, said cords connected with the slide and guided so pulling down on one cord will move the slide including the drapery thereon in one direction and pulling down on the other cord will move the slide in the other direction, said actuator having attached thereto a ring which serves as a guide and support for one of the cords.

4. In combination with the top rail of a window casing extending across each side casing and the intervening window space, a pair of drapery holders each having a bracket portion overlying and secured to the top of said top rail, each bracket portion having a depending part extending vertically in spaced relation to the front of the casing, an open-ended guide secured to the side of each of said depending members, a slide member in each of said guides respectively extending outwardly in opposite directions and having a supporting arm spaced from and held in parallel relation to the slide member with the space between the slide member and the supporting arm of each drapery holder free and open at their inner ends for directly supporting a drapery, an actuator arm rigidly connected to the

inner end of each slide member and extending to a point above the top rail, a pair of pulleys mounted on the top rail at one side only of the window, a pair of cords each passing over one only of said pulleys and being connected with the respective actuator arms, said cords extending horizontally in parallel relation along the top of the top rail, said cords being respectively connected with both slides and being guided to move both slides simultaneously in opposite directions, whereby pulling down on one cord will move both drapery holders including the draperies thereon toward each other and pulling down on the other cord will move both draperies in the opposite direction away from each other.
